HEARING AID CANAL TIP

John R. Beaudry, Minneapolis, Minn., assignor of one-half to John B. Beaudry, Minneapolis, Minn.

Filed June 27, 1966, Ser. No. 2,811

Term of patent 14 years

(Cl. D26—14)

FIGURE 1 is a perspective view of a hearing aid canal tip embodying my design;

FIGURE 2 is a side elevation view thereof;

FIGURE 3 is a top plan view of the same;

FIGURE 4 is a bottom plan view of the same, and

FIGURE 5 is a right end elevation view of the same.

The dotted lines in FIGURE 1 show a portion of a hearing aid unit normally connected to the tip and are included for illustration purposes only.

I claim:

The ornamental design for a hearing aid canal tip, as shown and described.
